UNITED STATES PATENT OFFICE.

STANLEY W. HAYES, OF RICHMOND, INDIANA.

DERAIL.

Application filed December 5, 1922. Serial No. 604,981.

To all whom it may concern:

Be it known that I, STANLEY W. HAYES, United States citizen, residing in Richmond, county of Wayne, State of Indiana, have invented the following described Improvements in Derails.

This invention is a derail having lost motion connections between the derailing member and a connecting rod whereby motion of one assists motion by the other. The derailing member may be hand operated serving through the lost motion connections to operate a target, or it may itself be operated by the said connections, but in either case it acts on acquiring momentum to deliver a hammer blow to said connections thus insuring completion of the stroke and jarring loose any mud, ice or other foreign matter which may have collected on the parts. The connections include an actuator with reference to which the derailing member is movable, and which has abutment surfaces spaced from and opposed to abutment surfaces on the derailing member. It is through these surfaces that the hammer action is effected, since in either direction of movement one of its abutment surfaces strikes the opposed abutment surface of the actuator a hamier blow as will be later described. This is advantageous particularly where the derail is hand operated, since it materially promotes ease of operation, and whether the movement is initiated by the derailing member or by the connections, insures its completion as stated.

The invention also relates to the provision of a latch automatically urged to locking position and to its incorporation in and correlation with the other parts of the derail.

In the single sheet of drawings, Fig. 1 is a plan of the open derailer; Figure 2 a rear elevation corresponding to Fig. 1; Figure 3 a vertical section on line III—III of Figure 2, and Figure 4 a like section on line IV—IV of Figure 3.

This invention finds its most satisfactory embodiment in a derail of the type in which the derailing member swings to and from the rail as in the structure chosen for illustration, which however must be understood not to be exclusive of other modes in which the invention might be applied.

In the illustrated derail, the base pro-

vided with front and rear walls 1, 2 and with side walls 3, 4, from which extend outward reinforcing spike flanges 6, is covered by the roof 7 so as to form an inverted open-bottomed box closed at the top except for the openings in which the operating and latching mechanism is mounted. The derailing member having the derail block proper 8, the hand hold 8' and the eye-lugs 9 is mounted to swing on or with the hinge pin 10 supported in the sides 3, 4. A stop 11 (Fig. 3) on the rear wall 2 and roof part 7 serves to limit the rearward swing of the derailing member. The actuator 12 is shown as a crank mounted on the hinge pin 10 coaxially with the derailing member, although it is not necessary that they should have the same axis. The actuator has a connection lug 13 for pivotal attachment to the connecting rod 14, the actuator and the derailing member being so mounted as to be capable of relative angular movement about the same axis. These parts are provided with pairs of front and rear co-acting abutment surfaces, those on the actuator being indicated by the numerals 15 and 16, and those on the derailing member by 17 and 18. The abutment surfaces on at least one of these parts are spaced so as to embrace the abutment surfaces on the other without being in contact with both at the same time and they are best placed symmetrically, those on the actuator with reference to the median plane of the actuator through its pivotal axis, and those on the derailing member with reference to a plane through its pivotal axis and preferably also through its center of gravity. It will be observed that the meeting surfaces of these abutments are not radial to the axis of the hinge pin 10, but such a relation is not excluded.

On reference to Fig. 4, it will be apparent that at the beginning of the stroke in either direction an abutment surface of each pair will be in contact and that on the operation of the actuator, or the swinging of the derailing member by hand, the inertia of rest of the derailing member will be overcome, and it will be raised to, or swung through, the point of unstable equilibrium acquiring momentum, overrunning the actuator, if the actuator is actuating the derailing member, and in any case moving with reference to it.

so that the corresponding abutment surfaces will separate and the previously inactive abutment carried by the derailing member will strike the opposed abutment of the actuator for a hammer blow and throw the actuator home. It will be observed that the hole in the roof 7, through which the actuator projects, is substantially the width of the actuator, allowing only for proper play, and that its walls 19, 20 limit sidewise motion.

The connecting rod 14 leads to a switch stand or target stand of familiar construction such for instance as those shown in my 15 Patents No. 1,185,662 dated June 6, 1916 and 1,312,691 dated August 12, 1919.

The latch which I have incorporated in this derail, and which as stated tends to move to locking position, is preferably a 20 gravity latch having members located in planes meeting at an angle, its upper or locking part 21 being arranged in angular relation to its weighted tail 22, which overbalances the latch into locking position, the 25 latch straddling or spanning the hinge pin 10 and being mounted to rock, in the vertical plane thereof and on a fulcrum constituted by the surface or surfaces 22' on the base against which the rear surface 22'' of the 30 latch bears, into the path of the lug 23 carried by the derailing member adjacent the hinge pin and having front and rear surfaces 24, 25, which when obstructed by the corresponding front and rear surfaces of the 35 member 21 of the latch lock the derailing member in closed or open position as will be obvious from Figure 3. The latch is thus loosely mounted, the bearing surfaces 22', 22'' being unconnected, but is kept in place 40 by the base and pin and may have its forward rocking movement limited by opposed portions of the base 21' as its rearward 45 movement is by lug 27 and adjacent parts of the base. It will be observed that latch member 21 is not symmetrical with respect to the vertical plane through its axis but that the rear surface which coacts with surface 24 is displaced to the rear and downward in order that the derailing member 50 may be locked in a suitable relatively low rearward position on the base.

The latch may be readily swung back out of locking position except when the hasp of a padlock 26 (Fig. 2) is looped through the locking eye-lug 27 obstructing part 21 of the latch. The straddling relation of the latch and the pin 10 is conveniently established by providing the latch with an elongated slot 28 adjacent the junction of the angularly related members 21 and 22 of the latch. In addition to this swinging or rocking movement in the plane of the axis of the hinge pin, the latch having the requisite play 60 may turn slightly transversely on the pin, its movement in either transversal direction

being limited by the downwardly projecting flanges of the hole in which it is located, the pivot of the latch being thus relieved entirely of strain. The mounting of the derailing member, the actuator and the latch 70 on the same pin and in line has the advantage of simplicity and compactness. It is not however an essential relation either as regards the derailing member and the actuator, as above pointed out, or as regards either or both of these members and the latch, nor is it intended to limit the application of the latch to a swinging derail.

Claims:

1. A derail comprising a derailing member, a connecting rod and lost motion connections between said parts whereby motion by one assists motion by the other.

2. A derail comprising a base, a derailing member pivoted thereon, a connecting rod, and lost motion connections between said parts including a pivoted actuator whereby motion by one of said parts assists motion by the other.

3. In a derail, a base, a derailing member movable thereon, and operative connections comprising an actuator having an abutment surface, said derailing member having an abutment surface spaced from and opposed to that of the actuator and adapted to strike the same a hammer blow after the derailing member has acquired momentum.

4. In a derail, a base, a derailing member pivoted thereon, and operative connections comprising a pivoted actuator having an abutment surface, said derailing member having an abutment surface spaced from and opposed to that of the actuator and adapted to strike the same a hammer blow after the derailing member has acquired momentum.

5. A derail comprising a base, a derailing member movable thereon, an actuator, and a connecting rod connected to the actuator, said derailing member and actuator having a lost motion connection comprising opposed abutment surfaces separated at each extreme position of the derail but coming into contact as the derailing member acquiring momentum strikes the actuator a hammer blow.

6. A derail comprising a base, a derailing member pivoted thereon, an actuator, and a pivoted connecting rod connected to the actuator, said derailing member and actuator having a lost motion connection comprising opposed abutment surfaces separated at each extreme position of the derail but coming into contact as the derailing member acquiring momentum strikes the actuator a hammer blow.

7. A derail comprising a base, a derailing member movable thereon, an actuator, and a connecting rod connected to the actuator, said derailing member and actuator having a lost motion connection comprising two sets

of opposed abutment surfaces, one of which is in contact at each extreme position of the derailing member and the other of which comes into contact after the separation of 5 the first set as the derailing member acquiring momentum strikes the actuator a hammer blow.

8. In a derail, a base, a derailing member movably mounted on the base, and an actuator 10 operatively connected to the derailing member, said derailing member receiving initial movement from said actuator but being free to overrun said actuator and complete its movement by momentum.

15 9. In a derail, a base, a derailing member movably mounted on the base, and an actuator, said derailing member and actuator having abutment surfaces adapted to coact in moving the derailing member to the point of 20 unstable equilibrium and to separate as the derailing member acquiring momentum overruns the actuator and finishes its stroke by momentum.

10. A derail comprising a base, a derailing member pivoted thereon and having a 25 pair of abutment surfaces, and an actuator having a pair of abutment surfaces, the members of one of said pairs being spaced and the other pair being interposed between 30 the spaced members, one of the members of each pair remaining in contact until the derailing member overruns the actuator and thereby assisting in raising the derailing member to its point of unstable equilibrium, 35 the derailing member finishing its stroke by momentum, and the other two corresponding abutment surfaces being adapted to so operate in the other direction of stroke.

11. In a derail, a base, a derailing member 40 pivoted thereon, and an actuator, the derailing member being free to overrun the actuator and finish its movement by momentum.

12. In a derail, a base, and a derailing member and an actuator therefor both pivotally supported on the base and independently movable around the same axis, and having cooperating abutment surfaces whereby the actuator initiates the movement 45 of the derailing member and the latter overrunning the actuator finishes its movement by momentum.

13. A derail comprising a base, a derailing member mounted thereon to swing off 50 and on the rail, and a latch located substantially mid-way of the stroke and adapted to lock the derailing member on or off the rail.

14. In a derail, a base, a derailing member mounted thereon to swing off and on the rail, and a rocking latch mounted on the base substantially mid-way of the stroke and adapted to lock the derailing member on or off the rail.

15. In a derail, a base, a derailing member 55 movably mounted thereon, means for mov-

ing the derailing member off and on the rail, a pin mounted on the base and extending lengthwise of the rail, and a latch straddling the pin and adapted to rock into and out of locking position with reference to 70 said derailing member, the latter being provided with a part for co-action with the latch.

16. In a derail, a base, a derailing member 75 movably mounted thereon, actuating means therefor, and a locking latch normally urged to locking position and mounted on the base to rock or turn in a plane parallel with the rail, and also to swing to a limited extent transversely of the rail in both directions 80 into contact with the base.

17. In a derail, a base, a derailing member mounted to swing thereon to and from the rail, an actuator pivoted co-axially with the derailing member, and a latch overbalanced 85 toward a position in which it locks the derail against movement and mounted in line with the pivotal mounting of the actuator and derailing member.

18. A derail comprising a base, a derailing member movable thereon off and on the rail, a pin mounted on said base and extending lengthwise of the rail, and a latch straddling 90 said pin and urged into the path of the derailing member.

19. A derail comprising a base, a derailing member hinged thereon to swing on and off the rail, a latch having a locking member and a overbalancing tail located in planes meeting at an angle and having adjacent 100 their junction a vertical elongated slot whereby the latch straddles the hinge pin of the derailing member, and means for limiting transverse movement of the latch.

20. A derail comprising a base, a derailing member hinged thereon by a pin extending lengthwise of the rail, a latch straddling 105 said pin and automatically moving to locking position said latch having locking surfaces at opposite sides of the vertical plane through the axis of the hinge pin for co-action with opposed locking surfaces carried by the derailing member, and a lug on the base in said plane having a hole to receive a padlock hasp to lock the derailing member 110 on or off the rail.

21. A derail comprising a base, a derailing member hinged thereon to swing on and off the rail, a pin by which said derailing member is thus mounted on the base and which extends lengthwise of the rail, and a latch straddling 120 said pin and bearing against the base and mounted to rock thereon, said derailing member having an abutment and said latch a corresponding abutment surface 125 adapted as the latch rocks to move into or out of the path thereof.

22. A derail comprising a base, a derailing member hinged thereon to swing on and off the rail and having an abutment surface, 130

a latch mounted to rock in a plane transverse of that in which the derailing member swings, into and out of the path of said abutment surface, and means for locking the 5 latch in the path of said abutment surface.

23. A derail comprising a base, a derailing member hinged thereon to swing on and off the rail, a pin by which said derail member is thus mounted on the base and which 10 extends lengthwise of the rail, and a latch straddling said p'n bearing against the base and having a limited rocking movement thereon in a substantially vertical plane, said derailing member having an abutment 15 and said latch a corresponding abutment surface adapted as the latch rocks to move into or out of the path thereof.

24. A derail comprising a base, a derailing member mounted to swing thereon on and off the rail, a loosely mounted gravity 20 latch having a bearing surface adapted to rock on a corresponding surface of the base into and out of the path of the derailing member, and means for keeping the latch in place while permitting a limited rocking 25 movement on the opposed un-connected bearing surfaces.

25. In a derail a latch having members located in planes meeting at an angle and

having adjacent the junction of said members an elongated slot. 30

26. In a derail a latch having members located in planes meeting at an angle and having adjacent the junction of said members a slot elongated in direction of the 35 length of the latch.

27. In a detail, a base, a derailing member having a hinge pin mounting on the base, an actuator mounted on the pin and operatively associated with the derailing member, and a locking latch for the derailing member straddling the pin and movable into and out of locking relation with said derailing member. 40

28. In a derail, a base, a derailing member pivotally mounted thereon, and a latch mounted to rock in the plane of the pivotal axis of the derailing member and into the path of a part of said member. 45

29. In a derail a latch having members located in planes meeting at an angle and having adjacent the junction of said members a slot elongated in direction of the 50 length of the latch, and bearing surfaces on the rear of the latch adjacent said slot. 55

In testimony whereof, I have signed this specification.

STANLEY W. HAYES.
